MEANS AND METHOD OF PRODUCING FABRIC

Application filed July 24, 1930. Serial No. 470,332.

This invention relates to new and useful improvements in means and methods of producing fabrics and particularly fabrics woven of metal, reed or other strands.

5 An object of the invention is to provide a machine or loom for the weaving of the fabric disclosed in application Serial No. 456,490, filed May 28th, 1930.

10 Another object is to provide an improved weaving means or machine including many advantageous features looking to cheapness of construction and efficiency in operation.

15 A further object is to provide an improved method of weaving whereby to produce a superior fabric.

An additional object is to provide an improved loom or weaving means including means for weaving diagonal strands together to form a diamond mesh in combination with 20 means for securing longitudinal strands to said diamond mesh by means of cross locking strands.

25 Yet another object is to provide a weaving means including means for feeding diagonal strands at right angles to each other, cutter means being associated with the feeder means to cut strands of the proper length from a source, shed forming means being provided whereby said strands are interlocked as they 30 are fed one across the other, and a second shed forming means and other feeder means being provided for securing longitudinal strands to the woven diagonal strands by means of cross strands.

35 A still further object is to provide an improved strand feeding means for weaving machines.

A further object is to provide an improved strand feeding and associated cutting means 40 for weaving machines.

A still further object is to provide an improved means of feeding the strands and fabric woven therefrom through the machine.

45 Yet a further object is to provide an improved operating means or power distributing arrangement for looms or weaving machines.

An additional object is to provide a weaving machine or loom including means for

weaving diagonal strands to form a diamond mesh and other means including a shed forming means to secure a longitudinal strand to the diamond mesh by means of cross strands, 55 said other means including means for offsetting either or both of the diamond mesh and longitudinal strands whereby the cross strands pass entirely to one side of the diamond mesh and entirely to the other side of the longitudinal strands.

Still another object is to provide a weaving machine including a shed forming means and fabric gripping means associated with the shed forming means to prevent the shed forming means from drawing the already 65 woven fabric.

Still a further object is to provide a weaving machine or loom including an improved strand guiding and fabric feeding means.

Yet another object is to provide an improved method of weaving.

It is also an object to provide improved shed forming means for use in weaving machines.

A further object is to provide an improved 75 means for and method of weaving a diamond mesh.

Other and additional objects and advantages will become apparent from the following description taken in connection with the 80 accompanying drawings showing one embodiment of the means of the invention. It is, of course, to be understood that the invention is not limited to the details shown and described but comprehends all such 85 changes or modifications as fall within the scope of the appended claims to which reference must be had for a definition of the limitations of the invention.

In the drawings:

Figure 1 is a plan view of the complete machine;

Fig. 2 is an end elevational view;

Fig. 3 is a horizontal sectional view on the line 3—3 of Fig. 2;

Fig. 4 is a sectional view on the line 4—4 of Fig. 1;

Fig. 5 is a detail showing a feed means;

Fig. 6 is a longitudinal sectional view 100 through a portion of the shed forming means

for the diamond mesh, cutters being shown;

Fig. 7 is a transverse sectional view of the shed forming means of Fig. 6;

Fig. 8 is a view similar to Fig. 6 but showing the shed forming means for the insertion of the cross locking strands;

Fig. 9 is a sectional view on the line 9—9 of Fig. 8; and

Fig. 10 is a sectional view on the line 10—10 10 of Fig. 8.

Referring in detail to the drawings, at 10 is shown the machine frame, the latter including uprights 11 and 12 and horizontal frame members 13 grooved as at 14 to receive 15 the edges of the table 15. This table is mounted in the grooves 14 for reciprocating movement to feed the fabric forward as it is woven and further the table is cut away as at 16 and 17 for a purpose to be described.

Extending upwardly through openings in 20 table 15 are a series of guide pins 18 and 19, the pins 18 at their lower ends resting against a cross bar 20 on an arm 21 and the pins 19 resting on a cross bar 22 on the same arm. 25 Coil springs 23 disposed about the spindles of the pins 18 and 19 bear at one end against the heads 24 of the pins and at their other ends against hollow blocks 25 carried by the table at its underside, the springs serving to 30 maintain the heads of the pins in contact with the cross bars.

Power for operating the machine may be supplied from any source to a pulley or coupling 26 on a shaft 27 arranged at one 35 side of the machine. At its forward end, beyond bearing 28, shaft 27 carries a beveled gear 29 meshing with a beveled gear 30 on a shaft 31 mounted in bearings 32 on the machine frame 10. A second beveled gear 33 on 40 shaft 31 meshes with and drives a beveled gear 34 on a shaft 35 mounted in bearings 36 and 37 and carrying a cam 38.

As shaft 35 is turned, it, of course, carries cam 38 with it and this cam is in engagement 45 with a roller 39 secured to the end of table 15 as on a pin 40. A coil spring 41 tends to move the table forward or toward the cam 38 and thus maintain the roller 39 in contact with the cam. The high point of cam 38 50 approaches the roller at the proper time, as will be explained in detail, and against the action of spring 41 moves the table rearwardly to feed the fabric through the machine, the spring 41 acting to again return the table to 55 normal position.

At its end remote from gear 34, shaft 35 carries a beveled gear 42 meshing with and driving a beveled gear 43 on a shaft 44 parallel with and at the side of the machine opposite shaft 27 and mounted in bearings 45 and 46. Mounted above table 15 and guided between uprights 11 and 12 is a sliding gate like member 47 including side members 48, webs 49, a top 50 and a reinforcing rib 51. At its 60 lower end member 47 carries a head 52 cut at

an angle along its front end as at 53 and carrying portions 54 and 55 of two sets of shed forming means.

Below table 15 is a second gate like member 56 also guided between uprights 11 and 12 70 comprising side portions 57, web portions 58, a bottom cross piece 59 and a reinforcing rib 60. At its upper end member 56 carries a head 61 including portions 62 and 63 of two sets of shed forming means, the same being 75 adapted to cooperate with the portions 54 and 55 respectively to form front and rear shed forming means, the construction and operation of which will later be described.

Rearwardly of the heads 52 and 61, the 80 table 15 has openings through which extend pins 64 for feeding the woven fabric through the machine. Pins 64 are quite similar to the pins 18, 19 and as clearly shown in Figs. 2 and 4 include a head 65 resting or bearing on 85 cross pieces 66 of an arm 67 similar to the arm 21. Further, coil springs 68 surround the shanks or stems of pins 64 and bearing against the heads 65 of the pins and blocks 69 on the underside of table 15 serve to maintain the heads in contact with the cross pieces.

A bracket 70, including a bearing portion 71 is arranged to dispose said bearing portion above the shaft 31, and in this bearing portion is a short shaft 72. Secured to shaft 90 31 to turn therewith is a gear 73, meshing with a gear 74 on shaft 72 to drive said shaft. Through the meshing of gears 73 and 74 shafts 31 and 72 turn together. On these shafts, to be turned thereby are lower and 95 upper feed rolls or members 75 and 76 respectively (see Fig. 5). Feed roll 75 is provided with a grooved periphery through which a wire 77 is fed.

Of course, the wire 77 is used in lengths or 100 cut into strands and the rolls 75 and 76 feed it in lengths. To this end the roll 76 has peripheral portions of two diameters and during the time the high or large diameter portion 78 is pressing on the wire 77 it will 110 be fed forward by the turning of the rolls and each time the small diameter portion 79 of roll 76 is over roll 75 the feeding of the wire is suspended to be resumed as soon as the portion 78 again comes over the roll 75. 115

Means are provided for cutting the wire 77 into lengths to provide the diagonal strands 80. On leaving the rolls 75 and 76 the wire 77 enters a guide 81 adjacent the rolls and at the side of guide opposite the 120 rollers there is disposed a lower stationary knife member 82 and an upper movable knife member 83. Knife member 83 is carried by lever member 84 pivoted as at 85 and for the purpose of automatically operating the 125 knife member 83 at the proper time, the upper wire feed roll 76 is provided with a pin 86 adapted to engage the free end portion of the lever member 84 to rock the same about its pivot bringing the knife member 83 into 130

position to cut off a length or strand 80 from the wire 77. Pin 86 is so disposed relative to the high portion 78 of the roll 76 that as the high portion leaves the roll 75, the knife 5 is actuated.

Arranged on the shaft 35 adjacent the end carrying the beveled gear 42 is a feed means for the wire 87 similar to that used for feeding the wire 77. This means for feeding the 10 wire 87 includes a peripherally grooved roll 88 on the shaft 35 and a gear wheel 89 also on said shaft the gear wheel and roll being adapted to turn with the shaft. A bracket 90 including a bearing portion 91 supports 15 a short shaft 92 in a position above the roll 88 and gear 89 and on this shaft 92 is secured a gear wheel 93 meshing with the gear wheel 89. Also, on the shaft 92 is carried a roll 94 having high and low portions as 20 in the case of the roll 76 whereby a length of wire is fed each time the rolls 88 and 94 make a complete revolution. These lengths form the cross strands 95 of the fabric.

Disposed adjacent the feed rolls 88 and 25 94 is a guide 96 (see Fig. 6) through which the wire 87 passes on leaving the feed rolls. This guide 96 guides the wire into the front shed forming means 54, 62 and disposed between the guide and the shed forming means 30 is mechanism for chopping the wire 87 into the strands or lengths 95. The mechanism for cutting the wire comprises a lower knife member 97 which may be stationary and an upper knife member 98 carried by a lever member 99 pivoted as at 100. A pin 101 on the roll 94, corresponding to the pin 86 on the feed roll 76, actuates the lever 99 which corresponds to the previously described lever 84 whereby to cut wire 87 into the lengths 40 95 as will be understood.

Means are provided for forcing the heads 52 and 61 toward each other at the proper time to have the shed forming means operate. To this end upright 11 carries an extension 45 102 to the upper end portion of which is pivoted a bell crank lever 103, the same being pivoted as at 104. The gate like member 47 at its upper side carries an adjustable bolt 105 against the upper end of which the short 50 arm of lever 103 bears. A pull-back spring 106 is secured at one end under a nut 107 of the bolt 105 and the other arm of this spring, which spring is U-shaped as shown, bears against the upper side of the end portion of the short arm. Long arm 108 of the lever at 55 its lower end carries a roller 109 held in engagement with a cam 110 on the shaft 27 by means of a coil spring 111. It will be understood that as the high point of the cam 110 60 presses against the roller 109 the lever 103 will be rocked about its pivot 104 against the action of spring 111 forcing the gate 47 and head 52 downward to the extreme low positions shown in the drawings. On the 65 high point of cam 110 passing the roller 109

springs 106 and 111 act to elevate the gate member 47 and the head 52 carried thereby.

A means quite similar to that just described is used for elevating the lower gate like member 56 and head 61 and the portions of shed forming means carried by the latter. To this end a bolt 112 is carried at the lower end of the gate like member 56 and the underside of the bolt is engaged by the end portion of the arm 113 of a bell crank lever 114 pivoted as at 115 to the lower end portion of the upright 11. The other arm, that is, the arm 116 of lever 114 carries at its upper end a roller 117 held in engagement with a cam 118 as by means of a coil spring 119. A U-shaped pull-back spring 120, corresponding to the spring 106, has the end portion of one of its arms secured beneath a nut 121 on the bolt 112 and has its other arm disposed over the free end portion of the arm 113 of the lever. As the cam 118, which is carried on the shaft 27, is turned its high and low points alternately engage the roller 117 and when the high point of the cam is in engagement with the roller the arm 116 of the lever 114 is rocked outwardly against the action of spring 119 forcing the gate member 56 and head 61 and portions of shed forming means carried by the latter upwardly toward the portions of shed forming means carried by the head 52 on the gate like member 47. It is to be understood that the heads 52 and 61 are moved downwardly and upwardly respectively at the same time by the action of cams 110 and 118.

Strands 80 are disclosed across the table between the guide pins 18 and 19 as shown and these strands are pushed along by the pins as the table is moved rearwardly by cam 38. The heads 24 of the pins 18 and 19 are as previously stated disposed on the cross bars 20 and 22 of the arm 21. This arm is secured to the shaft 122 and the action of the arm is the same as that of arm 67 since the action of arm 67 is imparted to the shaft 22, the arm being secured to said shaft. Therefore, it will be understood that the pins 18 and 19 projecting up through the forward portion of the table and separating and guiding strands 80 will carry the strands rearwardly as the table is moved rearwardly under the action of cam 38 and that as the pins 18 and 19 are moved below the surface of the table 15 on the high part of cam 124 leaving roller 123, pin 64 will likewise be moved below the surface of the table by springs 23 owing to the dropping of the arm 21 and cross bars 20 and 22. When the table again moves forwardly under the action of spring 41 all of the pins will be drawn forwardly with it and on the high portion of cam 124 again engaging roller 123 the pins will again be projected above the surface of the table in a position to guide and feed the strands 80 and the diamond mesh fabric woven at the front 130

shed forming means as well as the completed fabric.

The front shed forming means, that is, the diagonally disposed shed forming means comprising the upper and lower portions 54 and 62 operates through the opening 16 in the table 15. Upper portion 54 of this front shed forming means comprises a block as shown having at its front lower edge depressions 126 and projections 127, the latter in their lower faces being slotted as at 128 for the passage of the strands 95 and having slots 129 arranged at right angles to the slots 128 for the passage of strands 80. The lower portion 62 of the front shed forming means comprises a block having at its upper forward edge depressions 130 and projections 131 the latter in their upper faces being slotted as at 132 for the passage of the diagonal strands 95 and having slots 133 arranged at right angles to the slots 132 for the passage of the diagonal strands 80. Projections 127 enter depressions 130 and projections 131 enter depressions 126 (as detailed in Fig. 6) as the shed forming means are moved together. It will be obvious that the shed forming means moves alternate strands 80 and up and down to form a shed for the passage of strands 95 which latter remain straight.

The lower portion or block 62 of the shed forming means in the rear of the shed forming means carries a portion 134 forming an anvil against which diamond mesh woven at the shed forming means is clamped by means of pins 135 carried in the upper shed forming portion or block 54. A series of these pins is employed and the heads 136 of the pins are engaged by blocks 137 of rubber or other yielding compressible material, screws 138 being adjustable through the head 52 and against the blocks 137 to vary the tension on the individual pins 135. It will be understood, that these pins may be individually adjusted and that owing to the means just described that portion of the wire which has been woven will be clamped between the pins and the anvil 134 whereby the wire displaced by the shed forming means will be drawn from the free or unwoven portions of the strands 80 and will not draw the already woven fabric.

Shed forming means comprising the upper and lower portions 55 and 63 respectively are utilized in the attaching of longitudinal strands to the diamond mesh woven at the front shed forming means, the said longitudinal strands being attached by means of cross strands. As shown in the drawings the longitudinal strands are designated 139 and these strands enter the fabric by passing upwardly through suitable openings 140 in the head 61 and through the opening 17 in the table 15, this opening 17 also providing for the operation of the rear shed forming means through

the table. A wire feeding means similar to the feeding means previously described is mounted opposite the rear shed forming means and as shown this feeding means includes a lower roll 142 disposed on the shaft 44 and co-operating with a roll 143 disposed on a short shaft 144 mounted in a bearing 145 on a bracket 146 disposed above shaft 44.

Gear 147 on shaft 44 meshes with a gear 148 on the short shaft 144. Rolls 142 and 143 are the same as the rolls 75 and 76 previously described and act to feed a wire 149 forwardly in lengths, the length of the wire fed depending upon the width of the material being woven. On leaving the feed rolls the wire 149 passes through a guide 150 and then between upper and lower cutting blades or knives 151 and 152, the knife 152 being preferably stationary and the knife 151 being carried by a lever 153 pivoted as at 154 and automatically actuated as by means of a pin 155 on the upper feed roll, to chop the wire 149 into lengths or strands.

As already suggested the longitudinal wires 139 are attached to the woven diamond mesh at the rear shed forming means and this is accomplished by inserting cross or lock strands 156 cut from the wire 149. The rear shed forming means or the shed forming means comprising the upper and lower portions 55 and 63 comprise essentially similar blocks 157 grooved in their abutting faces as at 158 and each carrying a series of pins 159 and 160, the pins of the upper series being arranged opposite to and alternating with the pins of the lower series. This structure is detailed in Figs. 7, 8 and 9 and as shown each pin 160 at its end within the grooves 158 is notched or grooved to accommodate the cross or lock strand 156. Each of the pins 159 has a pair of grooves in its upper end, the grooves 161 accommodating the longitudinal strands 139 and the grooves 162 accommodating the cross strands 156.

From the drawings it will be apparent that the action of the rear shed forming means is such that the pins 160 engage the intersections of the diamond mesh woven at the front shed forming means, while the pins 159 engage the longitudinal strands 139 pushing the same upwardly through the woven diamond mesh. Thus it will be seen that the combined action of the pins 159 and 160 is such that a straight path is cleared for the cross or lock strands 156. However, it is not necessary that the diamond mesh be depressed downwardly while the longitudinal strands are pushed upwardly, since this action could be reversed and yet a straight path provided for the cross strand. Also, it will be understood that the positions of the pins may be reversed, the pins 159 being disposed in the upper portion of the shed forming means and the pins 160 disposed in the lower portion thereof.

Blocks 157 at each side of their groove faces 158 have side walls, the upper block having side wall 163 and the lower block having side walls 164. During the shed forming operation and the insertion of the cross or lock strands, the ends or surfaces of the walls 163 are in engagement with the previously woven diamond mesh pressing the same into contact with the surfaces of the walls 164 whereby the diamond mesh and that portion of the fabric which has been finished and passed beyond the rear shed forming means may not be drawn or pulled out of shape.

15 Means are provided for feeding the finished fabric from the rear shed forming means. This means includes the arm 67 which has cross bars 66 on which the heads of the pins 64 bear. The arm 67 has pivotal movement with a shaft 122 and beyond the shaft 122 carries a roller 123 in contact with a cam 124 on the shaft 27. During the time the roller 123 is in engagement with the high portion of the cam 124 the pins 64 are maintained in a position projecting above the table 15. The pins remain above the table during the rearward feed of the table under the action of cam 38 and at the time the high portion of cam passes the roller 39 to permit the table to be drawn forward by the spring 40, the high portion of cam 124 leaves the roller 123 permitting the arm 67 to drop with the shaft 122. This action on the part of arm 67 permits the spring 68 to draw the pins 64 downwardly below the surface of the table 15 and the pins are then carried forward to be again projected above the surface of the table when the latter reaches its former position, the cam 124 being so timed as to operate the arm 67 to push the pins above the table when the table has reached such foremost position.

From the foregoing description it will be seen that the improved weaving machine of the present invention includes many novel structural parts, combination of parts, and modes of operation and it is to be understood that the invention comprehends changes in the construction and arrangement of parts and all such variations in the mode of operation as fall within the scope of the claims.

It is desired to point out that the wire feeding means is of economical construction and that the length of the strand fed may be varied by placing different sized feed rolls in the various feeding mechanisms. It is also to be noted that owing to the arrangement of shafting about the machine space is economized and the machine frame supports all the shafting in a way to make the machine easily shiftable from place to place as occasion may require.

In connection with the operation of the machine attention is called to the fact that the alternate diagonal strands 80 are pushed

up and down rendering it unnecessary to crimp the strands 95 which are inserted straight. This provides high and low intersections in the diamond mesh woven at the first or front shed forming means and at the second shed forming means the longitudinal strands are so disposed that they pass only under the high intersections in the diamond mesh while the cross or lock strands pass over the low intersections in the diamond mesh. Owing to this arrangement the fabric is not materially thickened by the insertion or addition of the longitudinal and cross strands.

At the second shed forming means the low intersections in the diamond mesh are held stationary or pushed down slightly by the tools or pins 160 while the longitudinal strands are pushed or offset upwardly through the diamond mesh by the pins 159. Therefore, a straight path is provided for the insertion of the lock strands 156 and these strands need not therefore be crimped or offset and may be inserted in a straight condition.

Having thus described the invention, what is claimed is:

1. A method of weaving consisting in forming a shed through a series of strands, inserting a strand through said shed, feeding the fabric thus formed forwardly, forming a shed through said fabric and a third strand, and locking the third strand to said fabric by passing a fourth strand through the last named shed.

2. A method of weaving consisting in arranging a series of diagonal strands in parallel relation, offsetting the alternate strands up and down to provide a straight path extending over one strand and under the next, inserting a straight diagonal strand through said path whereby to form a diamond mesh, feeding said diamond mesh forwardly, clamping together the wires of said mesh at the last formed intersections thereof to prevent the woven portions of said wires being drawn, again offsetting the alternate parallel strands up and down and inserting a straight diagonal strand along the path thus formed.

3. The method of attaching longitudinal strands to a diamond mesh, the same consisting in passing said diamond mesh through a shed forming means, offsetting the longitudinal strands through said diamond mesh between the intersections thereof, and passing a cross strand through the shed formed by the offsetting of the longitudinal strands.

4. The method of attaching longitudinal strands to a diamond mesh having alternate rows of high and low intersections, the same consisting in passing said diamond mesh through a shed forming means, disposing the longitudinal strands under the high intersections of the diamond mesh, maintaining the

low intersections of the diamond mesh against upward movement, offsetting the longitudinal strands upwardly between the low intersections whereby to form a shed, and 5 passing cross strands through the shed thus formed.

5. In a fabric forming machine, a means for feeding a wire forwardly a determined distance, said means comprising a pair of 10 rolls disposed adjacent one another, means for rotating said rolls in opposite directions, one of said rolls having an enlarged peripheral portion, and the enlarged peripheral portion of the one roll adapted to press the

15 wire against the other roll during a part of each revolution of the rolls whereby a length of wire will be fed forward between the rolls equal to the length of the enlarged peripheral portion of the one roll.

20 6. In a fabric weaving machine, a shed forming means, said shed forming means including a block having alternate extensions and recesses, a second block having alternate extensions and recesses, the respective recesses and extensions of one block being arranged opposite the respective extensions and recesses of the other block, the extensions of each of the blocks having grooves in their faces for the passage of strands, one of said 25 blocks having an anvil portion to one side of its extensions and recesses, and the other of said blocks having projections to clamp a woven fabric against said anvil portion to prevent the same from being drawn when 30 portions of the strands forming the same are being acted on by the shed forming means.

7. A shed forming means to be utilized in the adding of strands to a diamond mesh fabric, said shed forming means comprising 40 a pair of oppositely disposed members having corresponding grooves in their opposed faces, said diamond mesh fabric adapted to be received between said members, shed forming means operating in the grooves of said 45 members, and the side walls of the grooves of the members adapted to clamp the said diamond mesh between them during the shed forming operation to prevent said mesh from being drawn.

50 8. The combination as in claim 5, including means for chopping off the fed portion of said length of wire on the high portion of the one roll leaving the other roll, said means including a pivotally mounted knife member, 55 and a means on one of said rolls for actuating said knife member.

9. In a weaving machine, a pair of heads, said heads arranged opposite each other, means to move said head towards each other, 60 and each of said heads carrying its respective portions of two spaced sets of shed forming tools.

65 10. In a weaving machine, a table, and means to guide and feed strands along said table, said means comprising a plurality of

pins having their heads disposed below said table, said table having openings through which said pins may be projected to have them extend above the table, spring means normally tending to move said pins to dispose them below the upper surface of the table, means to engage the heads of the pins, and means for actuating said means to project said pins above the table at predetermined times.

70 11. In a weaving machine, a table, means to reciprocate said table, means to guide and feed strands on said table, said last means comprising a plurality of pins adapted to project through the table to extend above the upper surface thereof, spring means tending normally to move said pins to dispose them below the upper surface of the table, means against which the heads of the pins bear and on which said heads may slide as the table is reciprocated, and means for actuating said means to have the pins project above the surface of the table during movement of the table in one direction and to permit the spring means to move the pins below the surface of the table on movement of the table in the opposite direction.

80 12. In a weaving machine including a frame, a table mounted for reciprocating movement in said frame, means for feeding diagonal strands across said table from one side, means for feeding diagonal strands across said table from the opposite side thereof, means for feeding strands across said table in the rear of said second strand feeding means, and shafting supported on the frame of said machine and extending about three sides thereof whereby to drive all of said strand feeding means, and means whereby all of said shafting is driven from a single source.

90 13. In a weaving machine, a table, means to reciprocate said table, means to feed strands on said table, said last means including means movable with the table and adapted to cause the strands to move with the table in one direction of movement of the table and to permit the table to move under the strands when the table is moving in the opposite direction.

100 14. In a weaving machine, a feeding means, said means comprising a series of pins, means for moving said pins in two directions, and said pins adapted on movement in one direction to move the woven fabric and on movement in the opposite direction to return to normal positions.

110 15. In a fabric weaving machine, a shed forming means, said shed forming means including a block having alternate extensions and recesses, a second block having alternate extensions and recesses, the respective recesses and extensions of one block being arranged opposite the respective extensions and recesses of the other block, the extensions of each of the blocks having grooves in their faces for the passage of strands, one of said 120 130

- blocks having an anvil portion to one side of its extensions and recesses, and the other of said blocks having projections to clamp a woven fabric against said anvil portion 5 to prevent the same from being drawn when portions of the strands forming the same are being acted on by the shed forming means, said projections comprising independently adjustable means each including a cushioning means. 10
16. In a weaving machine, a table, and means to guide and feed strands along said table, said means comprising a plurality of pins, said pins normally tending toward a 15 position below the surface of the table, and means for projecting the pins through the table at predetermined times. 16
17. In a weaving machine, a table, means to reciprocate said table, means to guide and 20 feed strands on said table, said last means comprising a plurality of pins adapted to project through the table to extend above the upper surface thereof, said pins tending normally to move to a position where they are 25 disposed below the upper surface of the table, means against which the heads of the pins bear and on which said heads may slide as the table is reciprocated, and means for actuating said means to have the pins project 30 above the surface of the table during movement of the table in one direction and to permit the spring means to move the pins below the surface of the table on movement of the table in the opposite direction. 17
18. A method of weaving consisting in arranging a series of strands in parallel relation, off-setting the alternate strands up and down to provide a straight path extending over one strand and under the next, inserting a straight strand through said path 35 whereby to form a two strand mesh, feeding said mesh forwardly, clamping together the wires of said mesh at the last formed intersections thereof to prevent the woven portions of said wires being drawn, again offsetting the alternate parallel strands up and down while said wires are so clamped, and then inserting a straight strand along the path thus formed. 40
19. In a weaving machine, a pair of heads, said heads arranged opposite each other, means to move one of said heads toward the other, and each of said heads carrying its respective portions of two spaced sets of shed forming tools. 45
20. In a weaving machine including a frame, a table mounted for reciprocating movement in said frame, means for feeding strands across said table from one side, means 50 for feeding strands across said table from another side thereof, means for feeding strands across said table in the rear of said second strand feeding means, a cam for moving the table in one direction, means for moving the table in the opposite direction, shaft- 55
- ing supported on the frame and extending about three sides of the machine whereby to drive said cam and all of said strand feeding means, and means whereby all of said shafting is driven from a single source. 70
21. In a fabric weaving machine, a shed forming means, said shed forming means including a block having alternate extensions and recesses, a second block having alternate extensions and recesses, the respective recesses and extensions of one block being arranged opposite the respective extensions and recesses of the other block, the extensions of each of the blocks having grooves in their faces for the passage of strands, one of said blocks having an anvil portion to one side of its extensions and recesses, and the other of said blocks having projections to clamp a woven fabric against said anvil portion to prevent the same from being drawn when portions of the strands forming the same are acted on by the shed forming means, said projections comprising independent means, and means cushioning said projection. 75
22. In a fabric weaving machine, a shed forming means, and means in the rear of said shed forming means to clamp together the wires of a mesh at the last formed intersections thereof to prevent the woven portions of the wires being drawn during the formation of the next shed. 80
- Signed at Bridgeport, in the county of Fairfield, and State of Connecticut, this 19th day of July, A. D. 1930.
